UNITED STATES PATENT OFFICE.

FRANK O. HOAGLAND, OF BRIDGEPORT, CONNECTICUT, ASSIGNOR TO UNION METALLIC CARTRIDGE COMPANY, OF BRIDGEPORT, CONNECTICUT, A CORPORATION OF CONNECTICUT.

PROJECTILE.

1,091,224.

Specification of Letters Patent. Patented Mar. 24, 1914.

Application filed November 24, 1913. Serial No. 302,614.

To all whom it may concern:

Be it known that I, FRANK O. HOAGLAND, a citizen of the United States, residing in Bridgeport, in the county of Fairfield and 5 State of Connecticut, have invented certain new and useful Improvements in Projectiles, of which the following is a specification.

This invention relates to projectiles of the general class known as expanding bullets,— 10 also sometimes designated as "mushrooming" bullets,—and relates especially to such projectiles for use in small-arms.

A principal object of my present invention is to furnish a projectile of that class, 15 which shall be adapted to be made of small diameters and elongated form, and capable of being fired at high velocities without prematurely breaking up, while readily expanding in an effective manner when meeting any considerable resistance.

In the accompanying drawing forming a part of this specification, I have illustrated my present improvements as applied in a preferred form thereof to a small-arms projectile of a well-known elongated and pointed style or form usually made in sizes ranging between two-tenths and four-tenths of an inch in diameter.

In the drawing, Figure 1 is a side view, on 20 an enlarged scale, of a projectile made in accordance with my present invention and having the multi-part core-casing. Fig. 2 is a sectional side view, and is drawn in alinement with Fig. 1, to facilitate comparison therewith. Fig. 2^a is an end view drawn in alinement with Fig. 2, and showing the projectile as seen from the right-hand in Figs. 1, 2 and 6. Fig. 3 is a sectional side view similar to Fig. 2 but drawn as a diagram, for illustrating in an approximate manner an early stage in the operation of the projectile or bullet, when subjected to initial expansion by striking a yielding but resistant object or target. Fig. 4 is a similar diagrammatic view for illustrating a later stage of the operation whereby the elongated core is reformed into a broadened bullet-head. Fig. 5 is a cross-sectional view in line Y—Y of Fig. 3, of the main core-case, which is designated in a general way by H. Fig. 6 is an enlarged diagrammatic side view for more fully illustrating the invention, and especially the character and relations of the combined deformation-limiter 40 and core-metal support which, in the pre-

ferred form thereof herein shown, is designated in a general way by J.

Similar characters designate like parts in all the views.

Heretofore in this art, bullets of an elongated form have sometimes been so made as to be crushable at the point-end, and thus become distorted in an erratic and irregular manner, by the so-called "mushrooming" action, but without a substantial reformation to a larger size, and without eliminating or sufficiently reducing the normal tendency,—which is particularly serious when using high-power explosives,—of the crushing action to break up and scatter the core-metal. It is, therefore, an object of my present improvements to avoid those objectionable results, by furnishing a projectile construction, as hereinafter more fully explained, whereby the rearward part of the core-metal may flow forwardly during the period of target-resistance, out of the base-tube portion of a main core-case and become joined and incorporated with the more forward portion of the core-metal and thereby reform or reshape the core,—by a method essentially reconstructive as distinguished from the former destructive action,—into a relatively compact and tenacious mass or bullet-head of a much larger diameter and located forwardly of the base-tube.

The shell or "jacket" H of the projectile or bullet, herein designated as the main core-casing, consists of a suitable tube preferably shaped at its forward end to receive a point-case, as P, and preferably provided at its rearward end with an integral head as h; in some instances however, this disk or head, h, may be omitted. The jacket or casing H may be made of various materials,— and produced by turning or drawing processes, as desired,—but I may use as a material therefor any suitable metal or alloy.

The forward end, as 2, of the jacket H is preferably reduced in diameter to interlock the jacket with core C, and also to receive thereon the rearward edge 3 of the point-case P, which is shown in Figs. 1, 2 and 6 fitting closely upon said reduced end-portion 2 of the jacket. This over-lapping zone of the core-inclosing members H and P, may, in practice, be located substantially midway of the pointed portion of the bullet, these being about the proportions selected for illustration herein. This arrangement

of said over-lapping members is found in practice to effect a suitable apportionment of the core-metal quantities, as regards the expanding operation when the projectile strikes either a yielding or a highly resistant object or target. This arrangement also provides for a longitudinal movement or telescoping action of the members H and P. (each relatively to the other, on the beginning of the flowage of any part of the core metal within said member P,) and therefore provides for an instant and a proper mode of action directly the point of the bullet meets with any considerable resistance, as more fully described in my co-pending application, Serial Number 779,657, filed July 18, 1913, my present invention being in some respects in the nature of an improvement on and applicable to the construction set forth and claimed in my said prior application.

The point-case member P may usually be made thinner than the tube or shell H, and of a relatively ductile material, since in the final operation, it is deemed to be desirable for the expansion to begin in this cap piece P, before the open forward end, 2, of the point-tube t shall begin to give way. The member P, in the form thereof which I prefer, may have one or more indented parts, as 5, forming retaining points which, by extending into the core-metal, hold together the point-case P and the core C,—see Figs. 1, 2 and 2^a,—without any direct attachment or interlocking of the member H with the member P.

The forward open end, 2, Fig. 2, of the main core-case H being fitted closely within the rearward end 3 of the point-case P, when the projectile is going at high velocity and the point 4 meets any considerable resistance, the said jacket end 2 operates within the point-case and at first, after the manner of a piston, and thus tends to force the flowable-metal, at c' , in the point P, forward and outwardly. Also, and at the same time, the forward outer zone at 2 of the point-tube t of the jacket, especially when made somewhat tapering as illustrated, naturally operates as a wedge to assist in effecting or inaugurating an initial expansive movement in the rearward part of the said point-case. These initial features of the expansion and re-forming operation, tend to open out the point-case approximately after the manner indicated in the diagram, Fig. 3, and thereby form an annular outlet at 7, through which the inner metal may begin to flow out, and thus permit a continuance (under a reducing projectile speed) of the forward movement of the jacket H during the upsetting of the point case by the resistance at 4. Thus, at this early stage of the operation, the metal in the core-point, c' , is resisted from the front by the crushing in 60 of the point 4 of the point-case, while be-

ing driven forward by the pressure of the filled jacket H. During this time, as will now be evident, the point-case will normally be rapidly expanded in advance of the expansion of the main core-casing H, into a broader cup-shape,—or “umbrella” form about as indicated by Fig. 4,—while the jacket itself is rapidly retarded in velocity. But the jacket being of relatively stable metal, while its core C is relatively mobile or fluid in character (after the manner of lead or soft alloys), this core C tends to continue its forward movement, and so flows forward and outward around the re-forming jacket-end, to thus form a substantially enlarged bullet-head about such, for instance, as described in connection with Figs. 3 and 4. The said point-case P, is thus reformed by the opposing forces and the flowing core-metal, into a guide-cup,—as P, Fig. 3,—of relatively shallow form and enlarged size. The flowing stream of metal normally attains great force during the medial stage of the expanding operation (Fig. 3), with the result that after this operation is well advanced, the forward end of the point-tube itself naturally turns outwardly and then will be curled or turned backwardly (see 2^a, Fig. 4), thereby forming an enlarged forward end on the jacket H for assisting in maintaining the re-formed core-metal in a compact mass, while this is driven forward by the combined force or momentum of that mass and of the core-casing H.

In applying my present improvements to the particular kind of expandible projectile shown in the drawing, I prefer to make such a reduction in diameter of the forward end of the main core-case H, as will bring the cross-sectional area at the telescoping zone at 2, to a substantially smaller size, preferably about one-half of the area of the base-portion of said main-core casing. These are, however, only approximate proportions, and, when taken in connection with the substantially conical construction of the telescoping portions of said members H and P, are found, in practice, to give a suitable initial resistance to deformation of the member H relatively to the point portion of the projectile.

My present improvements relate more especially to means for the regulation, and limitation, of the extent of the deformation,—or outward and backward turning,—of the deformable wall t , which after this operation has a form analogous to the curved parts 2^a, Fig. 4. This object I accomplish by the provision of the feature which I have designated as the “limiter”, or “deformation-limiter”, and by certain combinations therewith. For convenience in explaining those features, in Fig. 6 the projectile is shown divided into base-zone B, mid-zone M, and point-zone N, as indicated by the

lines 10, 12, 14 and 16. The rearward part t' of the core-casing is in the zone B and is the "base-tube"; the forward part t of the main-core-casing H is in the mid-zone M, and is the "point-tube"; and the "point-cap" is in the point zone N,—see Fig. 6.

For making and locating the deformation-limiter, an annular reinforcement, as J, Fig. 6, may be formed or fixedly applied within 10 the tube H, and be located at that point in the length of said tube to which the deformation or turning back of this tube should be limited. In practice I find the preferable location to be adjacent to the beginning 15 of the point-curve of the projectile, as well shown for instance, in Fig. 6 where said point-curve extends from the line 12 to the point 4. When the several parts are thus organized, the tube-zone, or base-tube, B, is 20 strengthened at its rear end by the head h , and at its forward end by the said reinforcement at J, and thus normally has an increased stability as compared with the tube-length, or zone M, as regards the power 25 of the flowing core-metal to deform the tube during the stopping of the projectile by impact with a target; this action being herein designated as target-resistance.

In some cases an opening as indicated at 30 d^2 , Fig. 6, may be made in the head h , and this opening may be of any desired diameter relatively to the inside diameter of base-tube t' , in the zone B; when this construction is adopted, and the limiter J has a rearward 35 face, as r , Fig. 6, this face operates, as will be evident, to resist any tendency to forward movement of the core-metal within the tube or casing, as might otherwise be produced by the direct pressure of the powder or usual wad on the rear end of the core C of the projectile. Similarly, when a face or shoulder is formed at f' , this tends to hold the core against a too free forward 40 movement within the casing wall t .

45 In the organization here described, a further feature is the thickening of the tube H in the base-zone B, as compared with the wall t of the deformable zone M, about as illustrated in Figs. 2, 3 and 4, so that the said 50 deformation-limiter here consists of the forward part, at J, of the thicker wall t' , where this joins the thinner wall t ,—see Fig. 2. Where the walls t' and t join in and make up the limiter J, the narrow zone, as D, Fig. 55 6, may be said to constitute a structural element connecting the base-tube t' with the deformable tube t , and to also constitute the limiter-member, which is, therefore, in this instance, of the nature of a connecting element 60 of the relatively thick wall t' , as well as an annular reinforcement of the rearward edge, f , Fig. 6, of the relatively thin wall t . In this organization of the several details, the said connecting zone D has the inner 65 face f so shaped and located as to operate

after the manner of a shoulder or abutment against which the core-metal in the zone M will be supported during the acceleration of the projectile when this is shot from the gun-barrel, and which during the re-forming action supports a circumferential portion of the core-metal in opposition to the pressure applied by a target to the point of the projectile; thus the limiter-zone D has a plurality of features and at successive times has different and varying functions. On the wall t being turned back (as explained in connection with Fig. 4), by the out-spreading action, the bends 2^a may 70 continue turning backwardly until they reach the limiter J, which, by its increased stability, 75 interrupts such turning back operation and so limits the same to a definite location. 80

As will be seen by comparing Figs. 3 and 4 as these views are herein described, the normally non-expandable base-tube t' and the expandible point-tube t are joined with a junction-structure which is located in the zone D (Fig. 6) and is provided with an outwardly extending face as f ,—which is preferably also a forwardly extending face,—that is, during the early stages of the point-tube expansion, supportive of the outer portion of the core-metal which is within the point-tube, (as against the action of target-resistance), and that during the later stage of such expansion forms a kind of guide-face for the core-metal flowing forwardly and outwardly from within the base-tube t' , into the enlarged and reformed projectile-head indicated in Fig. 4. During these operations,—as also indicated in said views,—the expandible point-tube t is first deformed (as a point-tube) and is then converted or reformed into a supporting-base for the enlarged head of the expanded projectile; and when these operations are fully carried out, the said supportive face f , (as approximately indicated in Fig. 4), normally forms an inner zone of such supporting-base, as 2^a . In Fig. 6, the described supportive action of the said face or abutment at f , is diagrammatically indicated by the dotted lines S, which illustrate how the lines of 90 95 100 105 110 115 120 125 130

resistant force may, for the moment, form or "arch over" within the core-metal when the projectile meets target resistance, and thereby co-operate in the expansion and reforming of the point-tube from its initial and approximately conical form in Fig. 3 into the supporting-base of much larger diameter and of the described "umbrella" form.

In the operation of re-forming the projectile, this is accomplished,—as will now be evident,—by the direct-action of the target-resistance (this being applied mainly in a direction longitudinally of the core) combined with the outwardly-acting flowage-pressure of the core-metal within the point-

tube, this pressure being, of course, developed by the target-resistance in proportion to the momentum and rate of retardation. These forces operate within and relatively to the point-tube which,—for this purpose,—should have a metal-status or character made up of, or comprising, the features of shape, size and ductility or temper, and be so proportioned that the out-spreading action extends initially around the circumference of the tube while beginning at its forward end, and thence proceeds in a progressive manner toward the base-tube. Thus the core-case is re-formed for supporting the re-formed core-metal, while the core itself,—including that part of it within the base-tube,—is simultaneously re-formed into a bullet-head of larger diameter located forwardly of the base tube, and supported by the original point tube now out-spread as a backing therefor. In practice the metal-status and the proper proportioning of the point-tube may be readily ascertained and brought to a proper relation by the usual methods of trial and measurement, having in view the size and weight of the projectiles and the powder pressures and ranges to be employed in any given instance.

During the time while the core metal flows forwardly out of the base-tube t' , (see Fig. 4) the metal between the then reforming forward part of the main core-case, (as indicated at v, v , Fig. 4) and the spread-out point-cap 3, will be rapidly flowing outwardly while integrally connected with the core-metal that is moving forwardly within and relatively to the said base-tube t' , so that while the rearward part of the core-metal is normally carried forward by its own momentum it is also being drawn forward (by means of said integral connection) by the pull of the said outwardly moving core-metal in the annular zone v, v ; thus the continuity of the core-metal in a single elongated core coöperates with other features, (during the rapid retardation of the projectile by target-resistance,) in securing the complete and proper reformation of the small-diameter small-arms projectile into the enlarged form as herein set forth. And in this re-forming or re-construction of the elongated core into a broadened bullet-head, metal is supplied to the forming head at the rearward side thereof by drawing such supply from within the rearward part of the core-case, this action normally occurring during the later stage of the out-spreading of the point-portion of the main core-casing, from the form, at t , Fig. 3, to a form as approximately indicated at $2^a, 2^a$, Fig. 4.

Having thus described my invention, I claim:—

1. In an expandible projectile having a soft-metal core with an elongated core-point,

the combination with the core, of a tubular core-case comprising a base-tube and a point-tube having the forward end thereof extending over the rearward portion only of the core-point and having its forward portion arranged and adapted for re-formation by being turned outwardly and backwardly during the deformation of the projectile by target resistance, and said base-tube and point-tube being integrally united adjacent to the rearward end of the core-point and there provided with a deformation-limiter whereby to restrict the said re-formation of the core-case to the point-tube portion thereof. 70

2. An expandible projectile having an elongated soft-metal core, and having a main core-casing comprising a normally non-expanding base-tube and an expandible point-tube joined with the base-tube with a junction-structure provided with a face extending outwardly to the point-tube wall, and supportive of the outer portion of the core-metal which is within the point-tube. 85

3. An expandible projectile having an elongated soft-metal core, and having a main core-casing comprising a normally non-expanding base-tube and an expandible point-tube joined with the base-tube with a junction-structure provided with a face extending outwardly to the point-tube wall, and supportive of the outer portion of the core-metal which is within the point-tube, and a core-point extending forward of the point-tube. 90

4. An expandible projectile having an elongated soft-metal core, and having a main core-casing comprising a normally non-expanding base-tube and an expandible point-tube joined with the base-tube with a junction-structure provided with a face extending outwardly to the point-tube wall and supportive of the outer portion of the core-metal which is within the point-tube, and a point-cap on the core-point forward of the point-tube. 100

5. An expandible projectile having an elongated soft-metal core, and having a main core-casing comprising a normally non-expanding base-tube and an expandible point-tube joined with the base-tube with a junction-structure provided with a face extending outwardly to the point-tube wall, and supportive of the outer portion of the core-metal which is within the point-tube, and a point-cap on the core-point forward of the point-tube. 115

6. An expandible projectile having an elongated soft-metal core, and having a main core-casing comprising a normally non-expanding base-tube and an expandible point-tube joined with the base-tube with a junction-structure constituting a deforma- 125

tion-limiter for the point-tube, and provided with a face extending outwardly to the point-tube wall, and supportive of the outer portion of the core-metal which is within the point-tube, and a core-point extending forward of the point-tube.

7. An expandible projectile having an elongated soft-metal core, and having a main core-casing comprising a normally non-expanding base-tube and an expandible point-tube joined with the base-tube with a junction-structure constituting a deformation-limiter for the point-tube and provided with a face, as *f*, extending outwardly and forwardly to the point-tube wall, and supportive of the outer portion of the core-metal which is within the point-tube, and a point-cap on the core-point forward of the point-tube.
- 10 8. An expandible projectile having an elongated soft-metal core, and having a main core-casing comprising a normally non-expanding base-tube and an expandible point-tube joined with the base-tube with a junction-structure constituting a deformation-limiter for the point-tube and provided with a face, as *f*, extending outwardly and forwardly to the point-tube wall, and supportive of the outer portion of the core-metal which is within the point-tube, and a point-cap on the core-point forward of the point-tube.
- 15 9. An expandible projectile having an elongated core of a metal flowable under tar-

get-resistance, and having a tubular main core-case of more resistant metal and comprising a normally non-expandible base-tube integrally connected by a junction-structure substantially such as *J*, with a 40 point-tube having a reducing diameter forwardly from the base-tube and having the forward end thereof of a metal-status and proportioned and adapted for out-spreading around its circumference and from a beginning at its forward end, and thence progressively toward the base-tube, when subjected to target-resistance and to the core-metal flowage-pressure resulting therefrom, and thereby reform the core-case for 45 supporting the core-metal while the core is simultaneously reformed into a bullet-head of larger diameter located forwardly of the base-tube.

10. In a projectile having an incased core 55 of metal flowable by target impact, and having in a tubular main core-casing two zones of which the rearward zone is of relatively high stability and the forward zone of relatively high mobility, these two zones being 60 integrally joined by a narrow connecting zone constituting a limiting means whereby to regulate and restrict the reformation of the said forward zone during the expanding of the projectile by the target resistance, 65 substantially as described.
